UNITED STATES PATENT OFFICE.

JOSEPH H. TAYLOR, OF MELLEN, WISCONSIN, ASSIGNOR OF ONE-THIRD TO MILTON G. ROSS AND MILTON E. MEREDITH, BOTH OF MELLEN, WISCONSIN.

INNER TUBE.

1,427,036.

Specification of Letters Patent. Patented Aug. 22, 1922.

Application filed October 25, 1921. Serial No. 510,265.

To all whom it may concern:

Be it known that I, JOSEPH H. TAYLOR, a citizen of the United States, residing at Mellen, in the county of Ashland and State 5 of Wisconsin, have invented certain new and useful Improvements in Inner Tubes; and I do hereby declare the following to be a full, clear, and exact description of the invention, such as will enable others skilled in the art 10 to which it appertains to make and use the same.

This invention relates to new and useful improvements in cushion tires and more particularly to a cushion inner tube for use in 15 an ordinary shoe and has for its primary object the provision of means including cushioning springs for effectively supporting the shoe and capable of withstanding heavy loads and strain and which will provide the desired resiliency to reduce shocks 20 and jars without the annoyance and expense of punctures and blow-outs attached to pneumatic tires.

Another object of this invention is the 25 provision of an inner tube that may be easily and quickly assembled and disassembled to permit changing of any one of the parts when worn or broken and which will be simple, durable and efficient, and which may be 30 manufactured and sold at a comparatively low cost.

With these and other objects in view as will become more apparent as the description proceeds, the invention consists in certain 35 novel features of construction, combination, and arrangement of parts as will be hereinafter more fully described and claimed.

For a complete understanding of my invention, reference is to be had to the following 40 description, and accompanying drawings, in which:—

Figure 1 is a transverse sectional view illustrating my invention applied to a shoe and the latter mounted on a rim,

45 Figure 2 is a longitudinal sectional view illustrating my invention in the shoe,

Figure 3 is a fragmentary plan view illustrating the cushioning means and showing in dotted lines a part of the casing.

50 Figure 4 is a fragmentary side elevation, illustrating the manner of connecting the inner and outer bands and also the side plates.

55 Figure 5 is a detail sectional view, illustrating a portion of the casing which may

be bent back upon the casing to permit fastening of the ends of the outer band.

Referring in detail to the drawings, the numeral 1 indicates a cushioning means that includes inner and outer circumferentially 60 extending flexible bands 2 and 3 constructed from steel or any other material suitable for the purpose. The bands 2 and 3 have their edges bent to form flanges 4 that are notched at spaced intervals as shown at 5 to permit 65 flexing of the band. The outer band 3 has its ends detachably connected by a plate 6. The plate 6 has rivets 7 that extend through openings in the band 3 adjacent its ends. The plate 6 has formed integrally therewith 70 a pin 8 that extends through notches 9 formed in the ends of the inner band 2. The bands 2 and 3 at spaced intervals are provided with pins 10 to form spring seats and project in the ends of coil springs 11, the 75 springs 11 are positioned between the inner and outer bands and are tapered towards one of their ends. The springs have their smaller ends in contact with the inner band, while their larger ends contact with the 80 outer band.

A plurality of side plates 12 have their outer and inner edges curved inwardly as illustrated at 13 and are fastened to the flanges of the inner and outer bands 2 and 3 85 by fastening elements 14. The fastening elements 14 are of any desired construction and are capable of permitting the side plates to be detached from the inner and outer bands when desired. The ends of the side 90 plates slightly overlap each other and are pivotally connected by rivets or similar fasteners 15. The plates have formed thereon pins 16 that form seats for transversely arranged springs 17 that extend between the 95 springs 11 and are of coil formation. The pins 16 project a short distance into the ends of the springs 17 to prevent said springs from accidentally disengaging the plates 12 during the use of the device.

The pin or rod 8 formed on the connecting plate 6 also has a spring 11 mounted thereon and which spring bears against the connecting plate 6 and the notched ends of the inner band. The pin or rod 8 extends 105 through the rim 18 and the felly 19 of a wheel and has a nut 20 turned thereon. The rim forms the subject matter of a co-pending application filed October 1, 1921, and serially numbered 504,566. The cushion 110

means 1 after assembled is placed within a casing 21 constructed of rubber or any other material suitable for the purpose. The casing 21 is severed at its ends to permit portions 21' of said casing to be turned back so that the ends of the outer band may be connected and the pin or rod 8 passed through the notched ends 9 of the inner band. The pin or rod 8 passes through the 10 casing 21 and then through the rim and felly as before described. The casing 21 has placed against its interior wall filler elements 23 to form seats for the inner and outer bands and side plates to engage, and 15 are preferably constructed of rubber to increase the resiliency of the device. After the device has been assembled in the casing 21, the latter is positioned within an ordinary shoe 22' in a manner similar to the 20 placing of an ordinary inflatable tube within a shoe.

While I have shown and described the preferred embodiment of my invention, it will be understood that minor changes in 25 construction, combination, and arrangement of parts may be made without departing from the spirit and scope of the invention as claimed.

Having thus described my invention what 30 I claim is:—

1. A cushion inner tube comprising inner and outer circumferentially extending bands, cushioning means between said bands, side plates connected to the inner and outer 35 bands, and cushioning means between the side plates.

2. A cushion inner tube comprising inner and outer bands, means connecting the ends of the bands together, cushioning means between said bands, a plurality of side plates pivotally connected to each other and flexibly connected to the inner and outer bands, and cushioning means between the side 40 plates.

45 3. A cushion inner tube comprising inner and outer bands, pins secured to said bands

at spaced intervals, coil springs engaging said bands and receiving the pins in the ends thereof, pivotally connected side plates 50 flexibly connected to the inner and outer bands, pins secured to said side plates, and coil springs bearing against the side plates and receiving the last named pins in the ends thereof.

4. A cushion inner tube comprising inner 55 and outer bands having their edges bent to form flanges, said flanges notched at spaced intervals, springs interposed between the inner and outer bands, pivotally connected side plates flexibly connected to the flanges, 60 and having their edges bent to form flanges, and springs interposed between said side plates.

5. A cushion inner tube comprising inner 65 and outer bands, cushioning means between said bands, side plates connected to the inner and outer bands, cushioning means between the side plates, a tubular casing receiving the inner and outer bands and the side plates, and filler elements between the cas- 70 ing and the bands and the plates.

6. A cushion inner tube comprising inner and outer bands, cushioning means between said bands, side plates connected to said bands, cushioning means between said plates, 75 a casing receiving said inner and outer bands and plates and being severed at its ends to permit portions of said casing to be bent upon the casing, an attaching plate connecting the ends of the outer band, said 80 inner band having its ends notched, a pin carried by said attaching plate and extending through the notched ends of the inner band and through the casing and adapted to pass through the rim and felly of the 85 wheel and have a nut turned thereon.

In testimony whereof I affix my signature in presence of two witnesses:

JOSEPH H. TAYLOR.
